KNITTING MECHANISM

Horace Leslie Curtis, Gilford, N. H., assignor to
 Scott & Williams, Incorporated, Laconia, N. H.,
 a corporation of Massachusetts

Application August 26, 1948, Serial No. 46,232

10 Claims. (Cl. 66—115)

1

This invention relates to knitting mechanism and has particular reference to the mounting and guidance of needles and sinkers in proper relative positions in circular knitting machines.

It has been customary to mount the sinkers of circular knitting machines in proper relationship to the needles guided in slotted cylinders through the use of cylinder tops, or sinker rings, which are secured to the upper ends of needle cylinders and which are slotted and provided with annular guiding surfaces for interengagement with the inner ends of sinkers which are supported at their outer ends in sinker dials surmounted by sinker caps carrying the cams which act upon butts of the sinkers. This type of construction is illustrated in the patent to Scott 1,467,691, dated September 11, 1923, and the patent to Moss 2,333,667, dated November 9, 1943.

In coarse gauge knitting machines this construction is quite satisfactory. However, in fine gauge knitting machines, for example those containing four-hundred needles in the cylinder and adapted for the knitting of sheer ladies' hosiery, difficulties are involved in that it requires extreme precision of workmanship to insure that the angular spacings of the sinker guiding grooves are both uniform throughout the cylinder top and are also precisely uniformly related to the needle guiding slots of the cylinder. Any lack of uniformity in these relations will be reflected in the production of vertical streaks in the knitted stockings.

Furthermore, the construction of the cylinder top for proper sinker guidance carries it over the upper edge of the needle cylinder to such extent as to limit the vertical height of the bottoms of the needle slots which serve for the guidance and support of the needle shanks with the result that the needles are not adequately supported at their upper ends and are subject to flexures which, if not uniform, will also result in the production of vertical streaks in the stockings.

It is the broad object of the present invention to provide at the upper end of a needle cylinder means for insuring proper relationship between the sinkers and the needles to insure uniformity of their cooperation in the production of stitches. In achieving this, and in accordance with the invention, it also becomes possible to afford an improved degree of guidance and support to the upper ends of the needles so that their operations are maintained substantially more uniform than has heretofore been possible.

The attainment of the general objects of the invention indicated above, as well as subsidiary

2

objects particularly relating to details of construction and operation, will become apparent from the following description read in conjunction with the accompanying drawings, in which:

5 Figure 1 is a vertical section taken through a needle cylinder and associated parts embodying the improvements constituting the present invention;

10 Figure 2 is a greatly enlarged fragmentary section through the assembly of Figure 1 showing details of construction in accordance with the invention, the section being taken on the plane indicated at 2—2 in Figure 3;

15 Figure 3 is a section taken on the plane indicated at 3—3 in Figure 2 showing the same devices as are illustrated in Figure 2;

20 Figure 4 is an axial section similar to Figure 2 but showing a modified embodiment of the invention; and

25 Figure 5 is a fragmentary elevation looking at the right of Figure 4.

The needle cylinder 2 is provided with axially extending slots 4 in which are inserted walls 8 which provide between them slots for the reception and guidance of needles 10. The walls 6 between the slots 4 serve as the bottoms of the slots between the walls 8 and act as guides for the backs of the needle shanks.

30 A cylinder top 12 which is secured in the needle cylinder by screws 14 differs from the conventional cylinder tops in that it does not project substantially outwardly over the upper end of the needle cylinder and is not provided with radial slots for the guidance of the sinkers, being 35 provided merely with an annular flange 15 which by reception in slots in the inner ends of the sinkers serves to determine the vertical positions of these inner ends. In other words, the cylinder top plays no part in determining the circumferential positions of the sinkers.

40 As contrasted with previous constructions, the cylinder 2 is extended upwardly to provide extensions 16 of the walls 6 between which the inserted walls 8 are located. The upward extent of these extensions is subject to considerable choice and may be substantially above the level of the tops of the extensions shown in Figure 2. It will be noted that these extensions 16 represent additional extended support for the backs 45 of the shanks of the latch needles 10.

45 A conventional dial 18 is radially slotted to receive the outer ends of the sinkers 22 which are covered by the sinker cap 20 provided with the cams which act upon the sinker butts 24. The 50 inner ends of the sinkers 22 extend in the slots

between the wall extensions 16 above the upper ends of the inserted walls 8 and are provided with slots which embrace the flange 15 and with extending portions 26 entering the annular groove in the cylinder top below this flange.

The bodies of the sinkers are made of a thickness just sufficiently less than the widths of the grooves between the extensions 16 to provide for free radial movements of the sinkers during knitting operations. As will be evident, if this thickness were carried up to the hook and adjacent portions of the sinkers there would not be sufficient clearance between the sinkers and the needles to accommodate the yarn. Accordingly, the sinkers are relatively thin in their portions which cooperate directly with the yarn as indicated at 28 in Figures 2 and 3. While these sinkers may take various forms, they are desirably of the general type illustrated in said Moss patent, the construction being such as to prevent engagement between the sinkers and the needle latches.

The advantages of the construction which has been described will now be apparent. The portions of the sinkers adjacent to and directly cooperating with the needles in the formation of stitches are guided directly in the slots in the needle cylinder which support the inserted walls which in turn provide the slots for the guidance of the needles. It will accordingly be evident that the relationships of the sinkers to the needles are not subject to the inaccuracies with which two separate machining operations are carried out. The axially extending slots in the needle cylinder may be very accurately machined and uniformly spaced about the cylinder with the result that extremely precise relationships between the needles and the adjacent portions of the sinkers are insured. It may be noted that the accuracy of indexing of the sinker guide slots in the sinker dial is not of particular importance since these play relatively little part in determining the relationships of the sinkers to the needles. The sinkers are directly supported and guided by extensions 16 at their portions which are in the vicinity of the needles.

It will be clear that the extensions 16 may be carried to a height which is limited, not by the outward extension of the cylinder top, but solely by the lowermost position which is assumed by the yarn in the knitting operation. Accordingly, guidance for the back of the needle shank is afforded substantially higher than has heretofore been possible.

Figure 4 and 5 illustrate a modified embodiment of the invention designed to achieve the same end of insuring proper accurate relationships of the sinkers and needles. In this modification the needle cylinder 30 is slotted as indicated at 32 for the reception of the inserted wall members 34 leaving for the support of these wall members the walls 33. The inserted wall members may terminate as indicated at 36 adjacent to the end of the needle cylinder. The upper end of the needle cylinder is reduced in diameter as indicated at 38 to leave spaces between the upper ends of the wall members 34 for the reception of the lower ends of inserts 40 which are provided with upper portions 42 of increased thickness which may be arranged to overlap inwardly the upper end of the needle cylinder as indicated at 44. The outer edge portions 46 and 48 of these inserts are in axial alignment with the outer edges of the walls 33 and so serve for the support of the backs of the needles to heights

well above the upper end of the needle cylinder.

Sinkers 50 having their inner ends retained by the cylinder top 52 as in the previously described modification are guided for radial movements between the thickened ends 42 of the inserts 40. As will be evident, this construction provides for the accurate relative positioning of the needles and sinkers inasmuch as the inserts 40 may be very accurately ground so that both their lower ends 46 and their upper ends 48 are accurately aligned and symmetrical in the case of each insert about a common central plane.

The advantages of this construction is that sinkers may be used which are of uniform thickness throughout, the enlarged upper ends of inserts 40 serving to provide guiding slots which are thinner than the inserted wall members 34.

It will be noted that in both modifications there are present means providing axially extending slots for the guidance of needles in their axial movements and for providing axially extending slots for the guidance of sinkers in their radial movements including pairs of fitted, contacting, approximately radial surfaces maintaining accurate circumferential relationship between each sinker guiding slot and the adjacent needle guiding slots. These surfaces are, of course, not precisely radial, being parallel and disposed symmetrically on opposite sides of radial planes.

It will be clear that details of embodiment of the invention may be changed without departing from the principles of the invention, and, accordingly, it is to be understood that the invention is not to be limited except as required by the following claims.

What I claim and desire to protect by Letters Patent is:

1. A needle cylinder assembly for circular knitting machines comprising a slotted needle cylinder providing a series of axially extending walls and separate wall members located between said walls and extending radially outward therefrom, the wall members defining slots for the guidance of needles, said wall members terminating short of the ends of said walls, which wall ends thereby provide slots for the guidance of sinkers.

2. A needle cylinder assembly for circular knitting machines comprising a slotted needle cylinder providing a series of axially extending walls, and separate wall members located between said walls and extending radially outward therefrom, the wall members defining slots for the guidance of needles, said wall members terminating short of the ends of said walls, which wall ends thereby provide slots for the guidance of sinkers, the outer edges of said walls being axially continuous from the portions thereof between said wall members beyond the ends of said wall members to afford extended backing for the shanks of needles beyond the ends of the wall members.

3. In combination, in a circular knitting machine, a slotted needle cylinder providing a series of axially extending walls, separate wall members located between said walls and extending radially outward therefrom, needles guided in the slots defined between said wall members, said wall members terminating short of the ends of said walls, and sinkers guided between the ends of said walls.

4. In combination, in a circular knitting machine, a slotted needle cylinder providing a series of axially extending walls, separate wall members located between said walls and extending radially outward therefrom, needles guided in the slots

defined between said wall members, said wall members terminating short of the ends of said walls, and sinkers guided between the ends of said walls, the outer edges of said walls being axially continuous from the portions thereof between said wall members beyond the ends of said wall members to afford extended backing for the shanks of needles beyond the ends of the wall members.

5. In combination, in a circular knitting machine, a slotted needle cylinder providing a series of axially extending walls, separate wall members located between said walls and extending radially outward therefrom, needles guided in the slots defined between said wall members, said wall members terminating short of the ends of said walls, and sinkers having portions guided between the ends of said walls and hook portions of thickness less than the thickness of said guided portions.

6. In combination, in a circular knitting machine, a slotted needle cylinder providing a series of axially extending walls, separate wall members located between said walls and extending radially outward therefrom, needles guided in the slots defined between said wall members, said wall members terminating short of the ends of said walls, and sinkers having portions guided between the ends of said walls and hook portions of thickness less than the thickness of said guided portions, the outer edges of said walls being axially continuous from the portions thereof between said wall members beyond the ends of said wall members to afford extended backing for the shanks of needles beyond the ends of the wall members.

7. In combination, in a circular knitting machine, axially movable independent needles, radially movable independent sinkers, and a cylinder assembly, said assembly including means providing axially extending slots for the guidance of the needles in their axial movements, and separate means providing axially extending slots for the guidance of the sinkers in their radial movements, said two means including pairs of fitted, contacting, approximately radial surfaces maintaining an accurate circumferential relationship between each sinker guiding slot and the adjacent needle guiding slots, one of the surfaces of each of said pairs being on the means providing needle guiding slots and the other being on the means providing sinker guiding slots.

8. In combination, in a circular knitting machine, axially movable independent needles, radially movable independent sinkers, and a cylinder assembly, said assembly including means pro-

viding axially extending slots for the guidance of the needles in their axial movements, and separate means providing axially extending slots for the guidance of the sinkers in their radial movements, said two means including pairs of fitted, contacting, approximately radial surfaces maintaining an accurate circumferential relationship between each sinker guiding slot and the adjacent needle guiding slots, one of the surfaces of each of said pairs being on the means providing needle guiding slots and the other being on the means providing sinker guiding slots, said means providing needle guiding slots comprising wall members inserted in axially extending slots in a needle cylinder forming a part of said cylinder assembly.

9. In combination, in a circular knitting machine, a slotted needle cylinder providing a series of axially extending walls, separate wall members located between said walls and extending radially outward therefrom, needles guided in the slots defined between said wall members, sinkers located between adjacent needles, and means providing axially extending slots for the guidance of the sinkers in radial movements, each of said last mentioned slots having its width determined by a single wall member, so that both said width and the alignment of such slot with a wall member are substantially independent of the indexing of adjacent wall members.

30 10. A needle cylinder assembly for circular knitting machines comprising inserted wall members for supporting and guiding needles therebetween, and projections separate from said inserted wall members extending above and between said inserted wall members for positioning stitch drawing elements to cooperate with the needles so that said elements will be substantially centrally located between flanking needles irrespective of non-uniformity of spacing of the needles in their circle.
